[57] CLAIM

The ornamental design for a shoe sole, as shown and described.

DESCRIPTION

FIG. 1 is a bottom and left front perspective view of a shoe sole showing my new design;
FIG. 2 is a right side elevational view thereof, the dot-dash lines of a shoe upper being environmental only and forming no part of the claimed design;
FIG. 3 is a bottom plan view thereof, the top plan being plain and unornamented.

FIG. 2

FIG. 3
